(57) **CLAIM**

The ornamental design for an electrical contact, as shown and described.

DESCRIPTION

FIG. 1 is a front view of an electrical contact showing my new design;

FIG. 2 is a top plan view thereof;

FIG. 3 is a left side view thereof;

FIG. 4 is a right side view thereof; and,

FIG. 5 is a perspective view thereof.

The rear view is a mirror image of the front view. The bottom plan view appears the same as the top plan view.
